Des. 227,418

Patented June 26, 1973

227,418

NURSES CAP

Evelyn Waites, 793 Fairmont Place,
Bronx, N.Y. 10460

Filed May 2, 1972, Ser. No. 249,756

Term of patent 14 years

Int. Cl. 2—03

U.S. Cl. D2—230

FIG. 1 is a top plan view of the nurses cap embodying my new design.

FIG. 2 is a side view thereof.

FIG. 3 is a bottom view thereof.

FIG. 4 is a perspective view thereof.

FIG. 5 is a rear view thereof.

I claim:

The ornamental design for a nurses cap, as shown.
